UNITED STATES PATENT OFFICE

2,564,896

SOUND DEADENING GUN

Eric Gustafsson and John W. Baur, Chicago, Ill.,
assignees to Binks Manufacturing Company,
Chicago, Ill., a corporation of Delaware

Application June 17, 1946, Serial No. 677,322

1 Claim. (Cl. 299—140)

1 This invention relates to spray guns for the applying of sound deadening material to surfaces of material which under certain conditions would give out sounds when impacted, such as in the case of closing automobile doors, or the like.

Among the objects of the invention is to provide a novel spray gun for handling a viscous material in which there is a valved controlled passage passing to a nozzle where the material is sprayed by air under pressure, the passage being of ample size for affording full freedom for passage or flow of material to the nozzle, and the valve controlling such passage may be moved further than heretofore so as to effect a full opening of the passage leading to the nozzle.

Another object of the invention is to control the valve by compressed air or the like, such as that which is fed to the gun to cause the spraying of the material at the nozzle, so that the control valve will be fully opened to afford a clear and full passage of the material through the passage and to the nozzle, in lieu, as heretofore, of mechanically opening the control valve by a manual pressure on the trigger in mechanical association with the control valve.

Other objects, advantages, capabilities, features, and the like are comprehended by the invention and as will later appear, and as are inherently possessed by the invention.

Referring briefly to the drawings:

Fig. 1 is a view in side elevation of an embodiment of a gun constructed in accordance with the invention;

Fig. 2 is a longitudinal sectional view of the same, showing a stage of use or operation;

Fig. 3 is a similar view, showing another stage of use or operation; and,

Fig. 4 is a transverse sectional view taken in a plane represented by line 4—4 in Fig. 2 of the drawings.

Referring more in detail to the drawings, the embodiment selected to illustrate the invention is shown as comprising a body 1, a handle 2, a head 3, and a nozzle 4. The body 1 may have a hook or eye 5 by which the gun may be hung or suspended, as from a hook, when the gun is not in use.

The forward end of the body 1 and the rear end of the head 3 are provided with sockets 6 and 7, and 8 and 9, of which sockets 6 and 7 are aligned, and sockets 8 and 9 are aligned. In sockets 6 and 7 fits a connector or union 10. Sockets 8 and 9 are oppositely threaded for the threading therein of a similarly threaded connector or union 11

which, when turned by a suitable tool, will tighten the body 1 and the head 3 together so that they will be in sealing abutment. The connector 10 is hollow to afford air passage as later described.

The head 3 has an air passage 12 leading from the socket 7 and the connector 10, and to an annular channel 13 provided in a forward threaded neck portion 14 of the head 3. The forward portion 10 of the body 1 has an air passage segment 12a leading to the socket 6 and the connector 10 for feeding air thereto.

The head 3 also has a material passage or chamber 16 of ample capacity for the facile movement of the material fed thereto from a duct or hose (not shown) connected to a threaded neck portion 17 forming a part of the head 3, as shown in Figs. 2 and 3. The neck portion 14 of the head 3 has a threaded socket 18 in which is threadingly connected a material nozzle 19 also having an ample capacity passage 20 for facile movement of the material therethrough. This passage communicates at its rear end through an opening provided in the side of the passage 16 and has a valve seat 21 with which is engageable a valve 22 connected to the forward end of a valve rod 23 slidably extending through the connector 11 and in the gun body 1, later explained.

The material nozzle 19 has a forward nozzle orifice part 24, where the material is ejected to be acted upon by compressed air to spray it, and further has a flange or collar part 25 adapted to sealingly abut with the forward end of the neck part 14 of the head 3 to normally close off the channel 13, but having a series of air orifices or passages 26 connecting with the channel 13.

On the flange 25 is seated a skirted portion 27 and a flange portion 28 of the nozzle cap 4, and with this flange portion 28 is engaged a coupling ring 29 which has a knurled and threaded portion 30 for connection or coupling with the threaded part of the neck portion 14 of the head 3. In this way the nozzle cap 4 is held in sealing contact with the flange 25 of the material nozzle 14. The forward end portion of the nozzle 4 has a discharge nozzle tip portion 31 provided with a discharge orifice 32 of ample capacity for the projection of the atomized material proceeding from the nozzle 24 and atomized by pressure air passing from the orifices 26 by way of the annular air nozzle passages 33 and 34 provided within the nozzle cap 4 between it and the nozzle tip portion 24 of the material nozzle 19 to communicate with the orifice 32 where the material from the nozzle 24 is aerated and atomized.

The handle 2 has passages 35 and 36 of which the passage 36 constitutes an air passage, the lower end of which has a connector 37 for coupling with a pressure air hose or duct (not shown) and the passage 35 is normally closed by a suitable means, such as a screw plug 38. At the upper portion of the handle 2 are air chambers 39 and 40 of which chamber 39 communicates by way of an air passage 41 in the body 1, which in turn leads to a valve chamber 42 communicating with a chamber 43 forming part of an air passage 44 connected to the air passage 12a. The chamber 43 is closed by suitable means, as a screw plug 45.

In the chamber 39 is a valve device comprising a valve body 46 suitably threaded into a threaded socket 47 forming part of the upper portion of the handle 2, and in the body 46 is a chamber 48 having air ports 49 for establishing communication between the chambers 39 and 48. The rear end of the body 46 has a sealing or packing means as a plug 50 for sealing off the chambers 39 and 40, and the forward end of the body 46 has a sealing or packing means 51 of any suitable form.

In these parts 50 and 51 is slidably mounted a valve element 52 which is of tubular form having an air passage 53 and an opening 54 at its rear end to communicate with the chamber 40, and having at its forward end transversed ports 55 adapted to establish communication between the chambers 48 and 53 when the valve 52 is in rearward or in position as shown in Fig. 3. Within the valve body 46 and around the valve 52 is a spring 56 reacting between a suitable shoulder in the valve body 46 and the sealing elements of the sealing means 50. On the rear end of the valve 52 is a collar means 57 adapted to abut against the sealing means 50 when the air valve 52 is in shut-off position (see Fig. 2), under the force of a spring 58 in the chamber 40 and reacting between the collar 57 and the rear end wall of the chamber 40. This spring normally maintains the valve 52 in closed or forward position, as shown in Fig. 2, and yields when the valve is positioned inwardly (see Fig. 3) into open position. The forward end of the valve member 52 has secured to it a knob or button B which may be pressed by the operator's finger to effect operation of the device.

Upwardly from the chamber 40 extends an air passage 59 leading to a diaphragm or piston chamber or cylinder 60 in which is reciprocably mounted a diaphragmatic member, such as a piston 61, and rearwardly of the piston or like member 61 and in the rear portion of the chamber 60 is a spring 62 which reacts between the piston-like member 61 and a closure cap 63 secured to the rear end of the piston chamber 60, to normally urge the piston forwardly (see Fig. 2).

Connected to the piston 61 is an air valve member having a body 64 slidable in a sealing means 65 secured, as by screw threads, to the body 1 at the rear of the chamber 42, and a seating portion 66 adapted to seat on a seat member 67 fixed in the body 1 at the forward end of the chamber 42 and between the chamber 42 and the passage chamber 43.

The material valve stem 23 is slidably mounted in this valve member 64 and extends rearwardly of the piston 61 where it has an adjustable head 68, as threaded to the stem 23, and held in adjust- ed position by a lock-nut 69 also threaded to the threaded end of the stem 23. Between the head 68 and the cap 63 reacts a spring 70 to normally urge the material valve stem 23 and the valve 22 in forward and closed position. The rear portion

5 of the piston 61 has a seat 71 against which the forward and tapered portion 72 of the head 68 may seat when the piston 61 moves rearwardly to effect an opening of the material valve 22.

10 The body 1 forwardly of the passage chamber 43 has a socket 73 in which is a sealing member 74 pressed by a spring 75 compressed by a plug 76 screwed into the socket 73, the member 74 acting to seal with the valve stem 23 and the hole in the forward wall of the passage chamber 43 in which the stem 23 slides in its sliding movements. The connector 11 is provided with a chamber 77 in alignment with a rear conical portion 78 of the valve 22 so that when the material valve 22 is moved into open position the portion 78 will extend into the chamber 77 so that the forward part of the valve 22 will be clear back and remote from the port of the valve seat 21 to afford free and unimpeded flow or movement of the material to the nozzle part 19 from the chamber 16. The rear portion 78 of the material valve 22 will be spaced from the forward end of the chamber 77 (see Fig. 3) to afford displacement of whatever material may have entered the chamber 77 when the valve 22 is moved into open position.

15 It will be understood that the piston-like member 61 may be of the flexible diaphragmatic form and thus reciprocate the same as a sliding type of piston member, and still perform the same functions and operations as herein disclosed.

20 In operation, and with the gun in closed condition as shown in Fig. 2, wherein the material to be sprayed is under pressure to the closed valve 22 and the pressure air is held at the closed valve 52, as also at the closed valve 66—67 the operator presses a finger against the button B to move the valve member 52 rearwardly and bring the ports 55 into communication with the chamber 39 (see Fig. 3), whereby the pressure air passes by way of passage 53 and port 54 of the valve 52 into the chamber 40 and thence by way of the passage 59 into the piston chamber 60. This air first moves the piston 61 rearwardly (against the force of the spring 62) with the valve 64 to open the air valve and port 66—67 whereby air immediately passes by way of chambers and passages 39, 41, 42, 43, 44, 12a, 12, 13, 26, 33, to the nozzle orifice 32. This is before any material is admitted to the nozzle orifice 32. Then further movement of the piston 61 will then cause its engagement with the head 68 on the valve stem 23 to start the movement of said stem 23 and the material valve 22 from its port 21, whence the material to be sprayed will flow to the nozzle chamber 20 and thence to the nozzle orifice 32 to be engaged by the air passing to said orifice for aerating and spraying said material. The piston 61 will then move back to a position as shown in Fig. 3 wherein the material valve 22 will be widely remote from the nozzle port 21 whereby there is ample passage space between the face of the valve 22 and the nozzle port 21 for free and unimpeded feed of the material to nozzles 24 and 31.

25 To stop operation the operator releases his finger from the button B whereby the spring 58 will move the air valve part 52 to the position shown in Fig. 2 whereby the ports 55 are closed from the chamber 39 and opened to the atmosphere whereby air in the piston chamber 60 will exhaust by way of the passage 59, chamber 40, port 54, passage 53, in the valve 52, to ports 55, and thence into the atmosphere. The pressure air, however, continues to flow by way of passage 36,

chamber 39, passages 41, 42, 43, 44, 12a, 12, etc., as aforesaid. The forward movement of the piston 61 permits the spring 70 to move the valve stem 23 and material valve 22 forwardly to closing position, and when the valve 22 closes its port 21, the piston will still continue to move, the air valve 66 still being open whereby air is still being projected at the air nozzle port or orifice 32 to blow off or cleanse any residual material that might be adhering thereto. Then further movement of the piston 61 will eventually bring the air valve 66 to closed position for shutting off further flow of air to the nozzle cap 31.

While we have herein described and upon the drawings shown an illustrative embodiment of the invention, it is to be understood that the invention is not limited thereto but comprehends other constructions, details, arrangements of parts, features, and the like without departing from the spirit of the invention.

Having thus disclosed the invention, we claim:

A spray gun for spraying sound deadening and viscous material, comprising a gun body having a nozzle structure provided with spacedly alined air and material nozzles having spacedly alined orifices and each also having a passage of relatively large and ample capacity leading to said orifices at the forward end of said nozzles and having an air passage leading to said air nozzle and to said nozzle orifice for spraying said material thereat, a material valve movable in said material passage for controlling the passage of said material therein and to said nozzle orifice, a valve in said air passage for controlling the passage of air under pressure therethrough, and

means normally spaced from an engageable part of said material valve and engageable with said material valve part and movable by the air passing into said air passage to move said material valve into a remote position to open up the full capacity of movement of material through said material passage to said nozzle orifice, said material passage having a chamber and said nozzle structure having a chamber communicating with said passage chamber at one side thereof, and means having a clearance chamber for said material valve at the other side of the material passage chamber for guiding said material valve to said opposite side of said material chamber and into said clearance to make full clearance of the passage of the material to said nozzle chamber.

ERIC GUSTAFSSON.

JOHN W. BAUR.
